UNITED STATES PATENT OFFICE.

JOHN PETER HUMMEL, OF MILWAUKEE, WISCONSIN.

SHIPPING-BOX.

1,148,685.

Specification of Letters Patent.

Patented Aug. 3, 1915.

Application filed June 1, 1915. Serial No. 31,424.

To all whom it may concern:

Be it known that I, JOHN PETER HUMMEL, a citizen of the United States, and resident of Milwaukee, in the county of Milwaukee, and State of Wisconsin, have invented new and useful Improvements in Shipping-Boxes, of which the following is a description, reference being had to the accompanying drawings, which are a part of this specification.

10 The invention relates to shipping boxes.

The invention designs to provide a shipping box of a construction, first, to meet the urgent demand of certain industries for a box having a separate cover or lid, second, one that can be conveniently loaded and be of sufficient stiffness that when so loaded can be piled or tiered end upon end or side upon side, so as to expose the contents for ready 20 inspection until such time when shipment is to be made, and third, so that the consignee or distributor of the goods contained in said boxes may open them for the purpose of inspection without defacing or in any 25 way weakening the structure of the box.

The invention further consists in the several features hereinafter set forth and more particularly defined at the conclusion hereof.

In the drawings, Figure 1, is a top view 30 of the box, parts being broken away and parts being shown in section; Fig. 2 is a side view of the box, parts being broken away and parts being shown in section; Fig. 3 is a detail sectional view taken on the line 3—3 35 of Fig. 2; Fig. 4 is a detail sectional view taken on line 4—4 of Fig. 1; Fig. 5 is a detail sectional view taken on the line 5—5 of Fig. 1; Fig. 6 is an end view of the box in collapsed condition.

40 The box comprises an open-ended box body A forming the sides, bottom and top reinforcing means, a cover B for the open end of the box, and means for removably securing said cover in place.

45 The open-ended box body A is made from a single strip of heavy fiber board, this strip being first suitably scored to provide for the proper folding of the same to form the box corners, and slotted to provide for flaps 5 50 which are bent over to meet in the center or overlap (as may be desired) when folded and glued together to form the bottom of the box (not shown) after which said strip is folded upon itself and the meeting edges 55 overlapped and fastened by any suitable means, all of which is well known construc-

tion. The box body is also slotted to provide for flaps 6 and 7 on opposite sides of the box and a bead 8 formed by scoring at the junctures between said flaps and the 60 sides of the box to permit said flaps to be folded down at an angle to the box body. These flaps 6 and 7 are not of great width, but sufficient, however, to provide a strong reinforcement for the open end of the box 65 when it is placed on its side or end. The ends 9 of each of the flaps are cut at right angles to the side of the box to which the flap is attached and consequently they will be parallel with the adjacent side of the 70 box. Now if it is desired to tier the boxes side on side both ends of the flaps 6 are brought under the flaps 7. Under these conditions, through the weight of the boxes above, the ends 9 of the flaps 6 will engage 75 the sides of the box to which the flaps 7 are attached and these flaps 6, being thus interposed between the ends of opposite sides of the box, will brace the sides at these points (as shown in Fig. 1) irrespective of 80 the cover which may be removed for inspection of the contents of the box even while it is stacked without defacing or in any way weakening the box structure. In case the boxes are stacked on end the ends of the 85 flaps 7 are brought under the flaps 6 and being similarly constructed will serve as braces in the same manner as pointed out in connection with the flaps 6. Thus the flaps 6 and 7, according to whether the boxes are 90 stacked or tiered side on side or end on end form reinforcements for the open end of the box which permits removal of the covers when it is desired to inspect their contents.

The cover B is of usual construction consisting of a single piece of material scored and slotted at its corners to form cover flaps 10, the ends of said flaps at the corners tapering from the top of the cover to the bottom edge of the flaps.

100 The means for detachably securing the cover in place comprises means for detachably securing the flaps of the cover to the box body. This means comprises a strip or band 11 of a width slightly greater than the 105 width of the cover flaps 10 which band is scored to fit the corners of the box body A and the ends of which are secured together by any suitable means as by overlapping the ends 12 and 13 and securing them together 110 with staples. The lower edge 14 of the band is secured by any suitable means, such

as staples 15, to the sides of the box body A, but these staples are fastened intermediate the edge of the sides so as to leave a free space 16 on each side of the box at each corner thereof so that the box may be collapsed as shown in Fig. 6. When the box is set up the corners of the bands come into place adjacent the corners of the box as shown in Figs. 1 and 3. The band 11 being secured 5 to the sides of the box in the manner above described pockets 17 are formed between said band and the sides of the box to receive the cover flaps 10 as shown in Figs. 2, 10 4 and 5. This band thus coöperates with 15 the sides of the box to form a plurality of pockets for detachably securing the cover flaps therein and are of a length to accomplish this purpose, but not of a length to permit water or moisture to collect between 20 them and the sides of the box which might result in an injury to the contents thereof. By this construction also the cover is made to fit down snugly upon the flaps 6 and 7 of the open end of the box body A thus preventing 25 rain, dust or dirt getting into the box from the top. Ordinarily the box is sealed by a sealing tape (not shown) so that breaking the seal of the tape permits the cover to be raised for inspection of the 30 goods.

The invention thus exemplifies a shipping box which is well adapted for the purposes specified.

The invention is not to be restricted to 35 the details of construction herein set forth, but may be varied so as to be within the scope of the appended claims.

What I claim as my invention is:—

1. A box comprising a box body having 40 an open end, a cover for said open end having flaps thereon, and means for removably securing said cover to said box comprising a band surrounding the sides of the box adjacent the open end thereof and fastened to 45 said box adjacent its lower edge to form a

plurality of pockets for receiving said cover flaps, said band being of a width slightly greater than the width of said flaps.

2. A box comprising a collapsible box body having an open end, a cover for said open end having flaps thereon, and means for removably securing said cover to said box comprising a band surrounding the sides of the box adjacent the open end thereof and fastened to said box intermediate the 50 corners formed by said sides to form pockets between it and the sides of the box for receiving said cover flaps. 55

3. A box comprising a box body having an open end, a cover for said open end having flaps thereon, means comprising a band surrounding the sides of the box body adjacent the open end thereof for receiving said cover flaps between it and the sides of said body to removably secure said cover thereto, 60 and means comprising flaps bent at angles to the side of the box body at the open end thereof to form a reinforcement for the box for the purpose specified. 65

4. A box body comprising a collapsible box body having an open end, a cover for said open end having flaps thereon, means comprising a collapsible band surrounding the sides of the box adjacent the open end thereof for receiving said cover flaps between it and the sides of said body to removably secure said cover thereto, 70 and means comprising flaps formed on the open end of the box body and bent at an angle thereto and having their ends disposed adjacent opposite sides of the box to contact therewith to reinforce and brace the sides of 75 the box to which said flaps are attached. 80

In testimony whereof, I affix my signature, in presence of two witnesses.

JOHN PETER HUMMEL
